[57] **CLAIM**

The ornamental design for a display unit and candle holder, as shown and described.

DESCRIPTION

FIG. 1 is a front elevational view of a display unit and candle holder showing my new design, the phrase "Happy Birthday" is shown in broken lines for illustrative purposes only and forms no part of the claimed design;

FIG. 2 is a bottom plan view thereof, the top plan view being a mirror image;

FIG. 3 is a right side elevational view thereof, the left side being a mirror image; and,

FIG. 4 is a rear elevational view thereof.
